UNITED STATES PATENT OFFICE.

JAMES H. PIERCE, OF BAY CITY, MICHIGAN, ASSIGNOR OF ONE-HALF TO JAMES H. BUDD, OF WILMINGTON, DELAWARE.

ENGINE.

1,034,732.

Specification of Letters Patent.

Patented Aug. 6, 1912.

Application filed September 18, 1911. Serial No. 649,811.

To all whom it may concern:

Be it known that I, JAMES H. PIERCE, a citizen of the United States, residing at Bay City, in the county of Bay and State of Michigan, have invented a new and Improved Engine, of which the following is a specification.

This invention relates to internal-combustion engines adapted to use liquid-hydrocarbons for fuel, and its object is to provide an engine whose operation may be changed instantly from two-cycle to four-cycle, and which shall be constructed so that the flow of the fuel can be regulated.

15 In the accompanying drawing, Figure 1 is a section of the engine on the line 1—1 of Fig. 2. Fig. 2 is a section on the line 2—2 of Fig. 1. Figs. 3 and 4 are details of construction.

20 Similar reference characters refer to like parts throughout the several views.

In two-cycle internal combustion engines, the burned gases are partially expelled from the cylinder by the air which has been compressed in the crank case. The remaining gases mix with the incoming air and thus weaken the force of the explosion. If a second scavenging occurs before the explosion, the amount of burned gases mixed with the 30 next charge of air will be negligible. In such case, however, it is necessary that the fuel be introduced into the explosion chamber at each alternative revolution only. It is also desirable that the amount of liquid 35 which will be introduced into the explosion chamber be under absolute control.

The engine shown is generally of well known design, and no invention is claimed to reside in the crank-case 1, cylinder 2, 40 water-jacket 3, piston 4, wrist-pin 5, connecting rod 6, crank-shaft 7 or air-inlet valve 8 having a control spring 9. Any other desired designs or constructions may be used in place of those named and shown in the 45 drawings.

On the crank-shaft is secured a pinion 11, which meshes with the gear 12 secured to the pinion 13, both revoluble on a pin 14. The pinion 13 meshes with the gear 15 secured 50 to the cam-shaft 16, revolvably mounted in the crank-case 1. Any other mechanism may be employed to drive this cam shaft so long as it is caused to revolve at half the speed of the crank-shaft. This shaft 16 is 55 hollow and in it is slidable the rod 17 hav-

ing a pin 18 projecting through the slot 19 in this cam shaft. At the outer end of the rod 17 is a groove into which extend the pins 27 carried by the lever 20, having its lower end connecting to the crank-case by means 60 of the link 21. A notched quadrant 26 guides the lever 20, and its notches receive the lip 22 which holds the lever in the desired position. A cam-sleeve 23 is slidable on the shaft 16 and is connected to the rod 65 17 by the pin 18. The cam 24 on one side of the sleeve increases slowly from nothing to maximum, while the cam 25 on the other side is constant.

Connecting into the cylinder 2 itself, or 70 into the passage 38, but preferably into the cylinder at a point above the lowest line reached by the upper surface of the piston, is a fuel pipe 28 which connects to the extension 29 of the fuel chamber 30. A rod 75 31 extends up from the cam-shaft and may be provided with a small antifriction roller 32 at its lower end. A collar 33 on the rod receives a downward thrust of the spring 34, the upper end of which presses against the 80 lower end of the extension 29. A valve 36 at the upper end of this rod 31 normally closes the passage from the fuel chamber 30 to the extension 29. A pipe 37 connects to a fuel-supply tank, which is under constant 85 pressure. A passage 38 connects the crank-case to the cylinder, an intake port 39 being opened by the piston. The usual exhaust port 40 will be opposite the intake port. The engine is supposed to turn to the left in 90 Fig. 1.

At the end of the explosion stroke, the compressed air in the crank-case will rush up the passage 38 and through the port 39 into the cylinder, expelling the larger portion 95 of the burned gases. The momentum of the engine will now carry up the piston and compress the air but no explosion will occur as there is no fuel. After the down-stroke, the piston again 100 compresses a charge of air in the crank case. At the end of the down stroke the piston opens the port 39 and the compressed air in the crank case displaces and replaces the air in the cylinder, which now has but 105 a small fraction of burned gases mixed with it. This point is shown in Fig. 1. Immediately after the piston has closed the ports 39 and 40, the cam 24 raises the rod 31 and valve 36, permitting a small amount of fuel 110

to be forced through the tube 28. This fuel will carburet the air and at the end of this compression stroke will explode. It will be clearly understood that when the 5 pipe 28 enters the cylinder above the port 39, "back-firing" in the crank-case is absolutely impossible, as no fuel enters the crank-case, and that when this pipe 28 discharges into the passage 38, such "back-firing" is also 10 impossible because the fuel is discharged into this passage only when the port 39 is open, so that the fuel will be carried up into the cylinder by the rush of air from the crank-case.

15 The amount of fuel which passes the valve 36 will depend upon the distance the valve is raised. For this reason the cam 24 is formed tapering and slidable on the cam shaft. When the cam is to 20 the right in Fig. 2, the valve 36 will be opened but a very short distance and but little fuel will enter the cylinder, but when the lever 20 is in central position, the valve will be opened full at each revolution of the 25 cam-shaft.

The engine described is therefore, a valve-less four-cycle engine, having all the advantages of engines of that type, and yet possessing the simplicity of construction of 30 the two-cycle engine. Because of the admission of the compressed air from the compression chamber at the end of the explosion stroke, a large portion of the burned gases is expelled, the remainder mixing with 35 the admitted air. The mingled air and gas are compressed during what is usually considered the scavenging stroke of the engine, and some power is required for this purpose, but the air and gases will take up 40 heat from the cylinder walls, and during what is usually the charging stroke of the four-cycle engine, will expand and more than return to the piston the power used to compress the air and gases. At the end of 45 this stroke, a fresh charge of pure air is admitted, expelling the air with the small amount of commingled burned gases, so that when the real compression stroke occurs, no burned gases are left in the cylinder.

50 It may sometimes be desirable to obtain maximum power from this engine, irrespective of slightly greater cost of fuel. This may be accomplished by forming the second cam 25 opposite the other cam 24.

55 When the cam sleeve is moved fully over to the left, as shown in Fig. 2, an injection of fuel will occur at each upward stroke of the piston and an explosion at each revolution of the engine. In other words, by merely 60 sliding the rod 17 and the cam-sleeve, the engine can be instantly changed from two-cycle to four-cycle or back and the fuel consumption can be absolutely controlled. This construction therefore presents an 65 engine having unusually great range in

power. It is to be understood, however, that this second cam 25 may be omitted, when the engine will be a "four-cycle" motor at all times, and such an engine is to be considered as embraced in the subject matter of the claims as well as one provided with both cams 24 and 25.

Having now explained my construction, what I claim as my invention and desire to secure by Letters Patent is:—

1. In an explosion engine, in combination with a cylinder, frame and main shaft, a cam-shaft, gears connecting the two shafts, a fuel receptacle, a valve to control the flow of fuel from the same, a rod connecting to the 80 valve and extending to the cam-shaft, a cylindrical sleeve on the cam shaft having two cams formed thereon to actuate the rod and valve when properly positioned, one of the cams tapering down to the cylindrical 85 sleeve, and the other cam extending a short distance along the opposite end of the sleeve, and means to convey the fuel from the receptacle into the cylinder.

2. In an explosion engine, a fuel receptacle adjacent the cylinder, a tube connecting into the cylinder above the intake port and to the fuel receptacle to convey the fuel, a valve to control the flow of fuel, a cam-shaft, a sleeve slidable thereon and revoluble 95 therewith, means for driving the cam-shaft at one half the speed of the engine, cams formed on opposite sides of the sleeve, one of greater length than the other, connecting means between the sleeve and valve whereby 100 the valve may be actuated by one or both cams at will, and means to position the sleeve on the cam shaft.

3. In an explosion engine, the combination of a cylinder and closed crank-case connecting by a passage, a piston slidable in the cylinder and adapted to open said passage at the inner end of its stroke to admit air from the crank-case, said cylinder having an exhaust passage in its wall adapted 105 to be opened by the piston at the inner end of its stroke, a crank-shaft and connecting rod in the crank-case, a cam-shaft in the crank-case and means to drive the same from the crank-shaft at half its speed, a fuel 110 receptacle, a pipe connecting to the receptacle and into the cylinder so that it may be closed by the piston immediately after the inlet and exhaust ports, a valve to control the flow of fuel from the receptacle, and 115 means actuated by the cam-shaft to open said valve at alternate strokes of the piston.

4. In an explosion engine, the combination of a compression chamber, a cylinder connected thereto by an air - passage and having an exhaust port, a piston adapted to open said passage and port at the inner end of its stroke, a crank-shaft, a cam-shaft, means connecting the shafts to drive the cam-shaft at half the speed of the other, a 120 125 130

fuel receptacle connecting to said cylinder, a valve to control the flow of fuel therefrom, and means operated by the cam-shaft to open said valve to permit the flow of the fuel.

5. In an explosion engine, the combination of a compression chamber, a cylinder connected thereto by an air passage and having an exhaust port, a piston adapted to 10 open said passage and port at the inner end of its stroke, a fuel receptacle connected to said cylinder, a valve to control the flow of fuel therefrom, and means operated by the engine at each alternate stroke of the piston 15 to cause the valve to permit the fuel to flow to the cylinder.

6. In an explosion engine, the combination of a crank-case, a cylinder connected thereto by an air-passage and having an exhaust port, a piston adapted to open said 20 passage and port at the inner end of its stroke, a crank-shaft, a cam-shaft mounted in said crank-case, means connecting the shafts to drive the cam-shaft at half the speed of the other, a fuel receptacle adjacent the engine and having a downward extension, a valve controlling the flow of fuel from the receptacle, a rod connecting to the 25

valve and extending down into the crank-case, and a cam on the cam-shaft adapted to 30 actuate the rod and valve.

7. In an explosion engine, the combination of a compression chamber, a cylinder connected thereto by an air - passage and having an exhaust port, a piston adapted to 35 open said passage and port at the inner end of its stroke, a crank-shaft, a cam-shaft, means connecting the shafts to drive the cam-shaft at half the speed of the other, a fuel receptacle adjacent the cylinder, a valve 40 to control the flow of fuel from the same, a rod connecting to the valve and extending to the cam-shaft, a cam on the cam-shaft revoluble therewith to operate the rod and valve, means to vary the effective operation 45 of the cam to cause greater or less movement of the valve, and a tube to convey the fuel from the receptacle into the engine.

In testimony whereof I have signed this specification in the presence of two subscribing witnesses.

JAMES H. PIERCE.
